UNITED STATES PATENT OFFICE

JOHN H. DEACON, OF GENOA, AND CARL H. HARTMAN, OF TOLEDO, OHIO, ASSIGNEES, BY
MESNE ASSIGNMENTS, TO ST. REGIS PAPER COMPANY, OF NEW YORK, N. Y., A COR-
PORATION OF NEW YORK

MATERIAL DISCHARGING DEVICE

Application filed June 13, 1929. Serial No. 370,688.

This invention relates to material-discharging devices, and more particularly to means for maintaining a discharge passage-way clear from clogged material.

In the following specification, the invention is disclosed as applied to the discharge tube of a packer for valve bags, and comprises means for applying compressed air to the tube to clear it of clogged material, whenever required.

In the accompanying drawing forming a part of this specification, Figure 1 is a partial sectional view of apparatus embodying the invention; Fig. 2 is a front view of the air-applying means and its connection to two filling tubes; and Fig. 3 is a side elevation of a portion of the mechanism.

A well known type of device for filling valve bags comprises a casing 10 enclosing a propeller 11 which forces material outward through a discharge opening 12 into and through a filling tube 13 into a valve bag, the valve of which is placed over the tube. Tube 13 is connected to a casting 14 which fits against casing 10, usually leaving a groove 15 therebetween through which a closing gate may slide.

In the construction shown, there is a passage 16 in casting 14 leading into the discharge passage at an angle. Passage 16 is connected by a nipple 17 to a horizontal pipe 18 fed by a pipe 19. In the construction shown, each end of a pipe 18 is connected to a passage 16 leading to a filling spout 13, and a valve 20 is provided in pipe 18 between each end and its junction with pipe 19. A handle 21 on a rod 22 operates the valve, which is normally closed but can be opened by depressing or otherwise operating handle 21. Rod 22 is guided by a bracket 23 attached to any suitable portion of the framework.

In operating the device, whenever material clogs in spout 13, it may be cleared by opening the associated valve 20. Passage 16 is directed towards the outlet end of the spout, so that the air tends to force material outward rather than back into the casing. When a gate in slot 15 closes access to the casing, the air clears the spout in front of the gate.

The clearing air may be applied at the beginning or at the conclusion of the filling of each bag, or it may be used only when clogging of the pipe renders it necessary.

In the particular embodiment of the invention disclosed in the drawing, the air supply is shown as provided for a filling device such as shown in the patent to Louis H. Hartman, No. 1,419,627, June 13, 1920. In this device the filling spout is mounted upon a weighing device, and a flexible sleeve 24 is provided for allowing limited vertical movement of the spout relatively to casing 10. When the spout-carrying frame drops in response to the weight of material filled into the bag, the gate is automatically tripped and closed.

It will be obvious that any material in the movable end of the spout is supported on the weighing device, and so is included with the material being weighed when the gate is tripped. If the same amount of material remains in the spout each time after the gate is closed and the bag removed, it may be classed with the permanent parts carried by the weighing device, and does not interfere with accuracy of weighing; but it will be readily understood that any irregularity in the amount of material remaining in the spout introduces a corresponding irregularity in the weighing. For this reason, unless the spout is cleared before each bag is removed, it should be cleared at the beginning rather than the end of the filling operation. However, when the pipe is cleared at the end of each filling operation, it avoids any difficulty arising from irregular amounts of material remaining in the spout. The action of the device is, of course, independent of whether a flexible connection or other joint is used between the casing and filling spout.

Various changes in the device shown and described can be made within the terms of the appended claims.

What we claim is:

1. In combination, a casing having a discharge opening, a propeller within the casing adapted to force material through the opening, a discharge spout having a cylindrical passage leading from said opening, there being an air passage through the side of said

spout into the side of said cylindrical passage and directed towards the discharge end of the spout, and means for supplying compressed air to said air passage.

5 2. In combination, a casing having a discharge opening, a propeller within the casing adapted to force material through said opening, a discharge spout having a cylindrical passage adapted to receive material from said opening, said spout being adapted to be mounted on a weighing device which may automatically close said opening, said spout having an air passage through its side into the side of said cylindrical passage adjacent the point where material is received from said opening, and means for supplying compressed air to said air passage.

10 3. In combination, a casing having a discharge opening, a propeller within the casing adapted to force material through said opening, a discharge spout having a cylindrical passage adapted to receive material from said opening, said spout being adapted to be mounted on a weighing device which may automatically close said opening, said spout having an air passage through its side into the side of said cylindrical passage adjacent the point where material is received from said opening, and means for supplying compressed air to said air passage, said air passage being directed towards the discharge end of said spout.

15 4. In combination, a plurality of filling devices each comprising a casing having a tangential discharge opening, a propeller within the casing adapted to discharge material through the opening, and a spout having a discharge passage in tangential alignment with said opening, there being an air passage through the wall of the spout into the side of said discharge passage directed towards the discharge end of the spout, a common pipe connected to said air passages, means to supply the pipe with compressed air and a separate valve for each filling device controlling the passage of the air from said pipe to said air passage.

In testimony whereof we have hereunto signed our names to this specification.

50 JOHN H. DEACON.
CARL H. HARTMAN.
